Re. 15,599

UNITED STATES PATENT OFFICE.

JOSEPH D. CITÉ, OF DAYTON, OHIO, ASSIGNOR, BY MESNE ASSIGNMENTS, TO THE
BAHMANN IRON WORKS COMPANY, OF DAYTON, OHIO, A CORPORATION OF
MASSACHUSETTS.

AXLE BEARING.

Original No. 1,290,511, dated January 7, 1919, Serial No. 196,321, filed October 12, 1917. Application for
reissue filed August 1, 1922. Serial No. 579,047.

To all whom it may concern:

Be it known that I, JOSEPH D. CITÉ, a citizen of the United States of America, residing at Dayton, in the county of Montgomery and State of Ohio, have invented new and useful Improvements in Axle Bearings, of which the following is a specification.

This invention relates to certain improvements in bearings for the axles of trucks or cars. More particularly the bearings are designed for use in connection with cars used for transporting brick in brick-making plants. In such places the car tracks are more or less imperfect in their laying, there being more or less variation in the elevation of the rails and, therefore, it is desirable that the bearings for the axles of such cars shall be free to compensate or vary in accordance with the amount of deflection that is imparted to the axles of the car due to such unevenness or lack of uniformity in track elevation and plane. The present invention has for its object to provide an axle bearing for cars of this character which has both a maximum of anti-friction and a facility for oscillating in planes both parallel and transverse and in fact any plane between planes that are parallel and transverse to the line of the axle of the car. In other words, the axle bearing is of the ball and socket or universal bearing type with an elimination of a certain amount of the contacting surface between the two members whereby friction at some points is avoided, and the parts of the bearing may be easily disassembled and put together. The invention consists of the parts and their combination and construction as will hereinafter appear from the description and the claims to follow and in connection with the accompanying drawings.

In the accompanying drawings which form part of the description to follow and upon which like reference characters indicate similar parts as they are illustrated in the drawings.

Fig. 1 is an end elevation of a car truck having my improved axle bearing in position thereon.

Fig. 2 is an inner side elevation of the bearing intact, detached from the truck or car frame.

Fig. 3 is a sectional view on the line 3—3 of Fig. 2.

Fig. 4 is a bottom plan view of one of the bearings intact with the axle broken away to facilitate space.

Fig. 5 is a sectional view on the line 5—5 of Fig. 3.

Fig. 6 is a sectional view on the line 6—6 of Fig. 2.

Fig. 7 is an end view of the ball or inner bearing member.

As hereinbefore stated, the invention is designed to afford the greatest range of oscillation of the bearing around the end of the shaft or axle which is received therein. This is important for the reasons hereinbefore stated; due to the imperfect alignment of the rails forming the track over which the car is moved and which are usually light. These cars, as before intimated, are used for transporting clay products in their making, such as bricks, tile, etc., for example in transporting the product in the green state to the kilns for drying the same.

Having these ends in view the particular description of the bearing is as follows:

1 designates a bracket which is rigidly attached to the truck or car frame 2. This bracket is strengthened or reinforced by a longitudinal rib 3 which is a well known expedient in the molders' art. The lower portion thereof terminates in a shell or housing which constitutes the outer member of the bearing. This shell or housing 4 is of spherical form which spherical form extends from the upper portion thereof into the sides thereof. The top and sides form a rounded interior contacting surface which incloses the ball or inner member 5 of the bearing. The lower portion of the shell or housing 4 is omitted or removed so that the bottom thereof is open as at 6, and it is apparent that the weight of the car will keep contact between the bracket 4 and member 5. As shown in Fig. 4 the ball member 5 of the bearing is exposed through the open bottom of the shell, the upper portion thereof being in contact with the upper rounded portion of the said housing, as is clearly shown in Fig. 5 of the drawings. The ball member of the bearing may be easily removed through the opening in the bottom of the shell or housing and replaced when it is desired to clean the bearing. It will be apparent that the ball member 5 is free to oscillate in any plane parallel to the line of

the axle 7; both in perpendicular and transverse planes as well as any plane between these two planes of oscillation. Therefore, it follows that a maximum of compensation is provided in the bearing for all inequalities or irregularities of the track. The axle 7 has a direct bearing in a series of roller bearings 8 which are assembled on the interior of the ball member of the bearing and these, together with the elimination of the lower portion of the housing 4, provide a minimum of frictional resistance at all degrees of oscillation which the axle may demand in passing over the car track. 10 The opening 9 in the housing through which the axle projects in finding its bearing is amply large to enable the greatest amount of oscillation of the ball 5. The wall 10 acts as a thrust bearing for the axle. The car tracks in brick kilns are usually not laid by expert trackmen. The conditions are such that it would be impossible to lay such track perfectly owing to the lack of a proper road bed and other causes well known to the brick-making art. Therefore, not only is there found inequalities in the track due to higher and lower elevation of parts, but often side deflections are present in these tracks and it is these various irregularities that render necessary a bearing of 20 the character described and shown, and which provides for any oscillation of the bearing that may be demanded by the axle, thus preventing damaging stress or strain 30 upon the axle or bearing, and insuring an easy running of the car.

Having described my invention, I claim:

1. The combination with a car axle, of a bearing therefor consisting of a housing the 40 interior top and side walls thereof being of a substantially spherical form and the bottom portion thereof being open, and an inner bearing member of spherical form within said housing, the lower side of said

inner bearing member being uninclosed at 45 the bottom of the housing, whereby it is subject to a universal movement within the housing with a substantial curtailment of frictional engagement with said housing.

2. The combination with a car axle, of a bearing therefor consisting of an outer housing or socket member the interior top and side walls thereof being of a continuous spherical form and the bottom thereof being 50 open throughout its width, a ball constituting an inner bearing member within said housing and adapted to have universal range 55 of movement therein, the lower side of said ball or inner member being exposed through the opening in the housing and said inner member having a series of roller bearings arranged therein which receive the car axle. 60

3. The combination with a car axle, of a bearing therefor consisting of a housing the interior peripheral top wall thereof being in the form of a frustum of a sphere and one of the side walls of the housing serving as a thrust bearing for the end of the axle and an inner bearing member having a form to fit within said housing, whereby it is subject to a universal movement 65 within the housing with a substantial curtailment of frictional engagement with said housing. 70

4. The combination with a car axle, of a bearing therefor consisting of an outer integral housing or socket member the interior top wall thereof being in the form of a frustum of a sphere and a side wall of the housing serving as a thrust bearing for the 80 end of the axle, a ball constituting an inner bearing member within said housing and adapted to have a universal range of movement therein, and said inner member having a series of roller bearings arranged 85 therein which receive the car axle.

In testimony whereof I affix my signature.

JOSEPH D. CITE.
